UNITED STATES PATENT OFFICE.

RICHARD H. GRIFFITH, OF BELLEVUE, OHIO, ASSIGNOR TO THE OHIO CULTIVATOR COMPANY, OF BELLEVUE, OHIO, A CORPORATION OF OHIO.

SOIL-PULVERIZER IMPLEMENT.

1,397,683.

Specification of Letters Patent.

Patented Nov. 22, 1921.

Application filed January 8, 1921. Serial No. 435,952.

To all whom it may concern:

Be it known that I, RICHARD H. GRIFFITH, a citizen of the United States, residing at Bellevue, in the county of Huron and State 5 of Ohio, have invented certain new and useful Improvements in Soil-Pulverizer Implements, of which the following is a specification.

My invention relates to improvements in 10 soil pulverizing implements, and more particularly to that class or type of earthworking implements commonly known as "packers and mulchers" in which front and rear gangs of parallel extending pulverizer 15 disks are employed, the ends of the axles of the front and rear gangs being mounted in and connected by reciprocate gang bearing members or yokes movably and slidably connected to the main implement or draft 20 frame.

The primary object of the invention is to provide a new implement of the class mentioned, which will not only be simple in construction and efficient in operation, but will 25 possess great strength and which will reduce the liability to disarrangement or injury to the parts to a minimum.

A further and very important object is to furnish a new construction and arrangement 30 of the gang connecting yokes, together with a floating arrangement of such gang connecting yokes with respect to the main frame.

A further object is to so mount the gang 35 yokes in the draft frame through the medium of guide members and rollers so that the draft will be transmitted in an improved manner to the front and rear gang axles and disk gangs and at the same time 40 permit the front and rear gangs of pulverizer disks to reciprocate or move in adjusting or conforming themselves to varying inequalities of the ground or surface being cultivated, the connections being such 45 as also that the draft stresses will be equalized at all times on such front and rear gangs of pulverizer disks in the varying positions of the latter.

It is an important object of my invention 50 to provide a floating arrangement of the axles and gangs of rollers which are designed to move over the contour of the terrain in such a way as not to affect the main frame as the floating frame conforms to 55 these several contours of the ground. It

is an object to provide such an arrangement that there will be no positive connection between the floating frame and the main frame but that the floating frame may be allowed to reciprocate freely and independently of the main frame and only to be guided by the main frame through the medium of the sliding contacts and the rollers. It is a further object of the invention to provide an arch-shaped member 60 that will reciprocate about a point removed from the main frame.

It is a further object to provide a ready means of disassembling the various parts associated with the floating arch so that they 65 can be renewed when they become worn.

With the above mentioned and other ends in view, the invention consists in the novel construction, arrangement and combination of parts, hereinafter described, illustrated 70 in one of its embodiments in the accompanying drawings and particularly pointed out in the appended claims.

Referring to the drawings forming a part 75 of this specification, Figure 1 is a front elevation of a soil pulverizer implement constructed in accordance with this invention, central portions of the disk gangs being broken away and some of the central front pulverizer disks being removed for the purpose of clearer illustration of the parts.

Fig. 2, a side elevation of the same.

Fig. 3, a side elevation of one of the draft frame end brackets, the gang yoke and yoke side members and bearings therefor being 80 removed.

Fig. 4, an end elevation of the same, the gang yoke guide retainer or bracket being restored.

Fig. 5, a side elevation of one of the gang 85 yokes detached, the gang axle shafts and the shaft and dust excluding end caps being removed.

Fig. 6, a disassembled sectional view of one 90 of the gang yoke bearing heads and the adjacent shaft and dust excluding caps carried thereby.

Fig. 7, an end and side elevation, respectively, of one of the anti-friction rollers for 95 the gang yokes.

Fig. 8, an end and side elevation, respectively, of one of the gang axle securing end caps.

The main or draft frame may be of any suitable and convenient construction, com- 100 105 110

pising, in the present instance, depending end bearing members or brackets 1, connected by transversely extending draft bars 2, the latter, in the present instance, being in 5 the specific form of angle bars.

The end brackets 1, terminate at their lower ends in heads 1^a, said heads 1^a, being provided with guides 1^b, in the present instance in the specific form of friction shoes 10 adapted to slidably engage with the lower sides of the gang yokes hereinafter described.

The implement is adapted to be drawn by means of a centrally located draft bar or 15 tongue 3, as shown in Fig. 2 of the drawings.

The improved implement preferably comprises front and rear gangs of soil pulverizer disks 4 and 5, respectively, the front pulverizer disks 4, being preferably larger in 20 diameter than the rear disks 5, and as a means of so mounting the front and rear disk gangs 4 and 5, as to permit an oscillatory or undulatory movement of such gangs to conform to or meet the varying 25 contour of the surface being cultivated, front and rear axle shafts 6 and 7, respectively, are provided, the disks 4 and 5, being preferably provided with suitable openings forming bearings and being loosely mounted 30 on the shafts 6 and 7, and the shafts 6 and 7, are connected at their ends by means of gang yokes 8, said gang yokes 8 being preferably of arcuate form and provided at their ends with bearing heads 8^a, provided with 35 openings adapted to removably receive and contain suitable bearing bushings 8^b, to removably receive and contain the ends of the axle shafts 6 and 7. The shafts may be retained by means of retainer caps 8^c, and 40 as a means of excluding dust and other foreign substances from the ends of the bearings the gang yoke heads 8^a, are preferably provided with dust excluding caps 8^d.

As a means of providing suitable anti-friction guides for the tops of the gang yokes 8, and for permitting the latter to ride freely thereunder in the reciprocatory movement of the same, anti-friction guide rollers 9, are mounted at the sides of the draft 45 frame members 1, on suitable axle bolts 9^a, and as a means of securing said guide rollers 9, in position and particularly as a means of removably mounting the gang yokes 8, beneath the guide rollers 9, and above the 50 guide shoes 1^b, suitable guide members or yoke retainers 9^b, are provided, said guide members, in the present instance, being in the specific form of V-shaped brackets and secured at their upper ends by means of 55 attaching bolts and nuts 10, and at their lower ends by means of attaching elements 60 11. 8^b designates the point removed from the frame about which the gang yokes 8 move.

65 It will be seen that the guide members

1^b, 9 and 9^b, securely retain the gang yokes 8, in proper position as against relative lateral displacement and side thrust, the guide members or yoke retainers 9^b, being also additionally secured by means of nuts 70 9^c, on the axle bolts 9^a.

Having thus described one of the embodiments of my invention, without having attempted to set forth all the forms in which it may be made, or all the modes of its use, 75 what I claim and desire to secure by Letters Patent, is,

1. A soil pulverizer implement, comprising a draft frame provided with guides, gang yokes slidable therein, and front and 80 rear gangs of pulverizer disks carried by said gang yokes.

2. A soil pulverizer implement, comprising a draft frame provided with guide bearing brackets, gang yokes carried by and slid- 85 able in the latter, and front and rear axle shafts and pulverizer disk gangs carried by and adapted to move with said gang yokes.

3. A soil pulverizer implement, comprising a draft frame, guides carried thereby, longitudinally extending gang yokes movable in said guide bearings, means for detachably mounting said gang yokes in the latter and front and rear pulverizer disk 90 gangs and axles carried by said gang yokes.

4. A soil pulverizer implement, comprising a draft frame including longitudinal guides, longitudinally extending upwardly curved gang yokes slidably movable in said 100 guides, means for detachably retaining said gang yokes, and front and rear pulverizer disk gangs carried by said gang yokes and moving therewith.

5. A soil pulverizer implement, comprising a transversely extending draft frame provided with end brackets having guides, arcuate gang yokes removably mounted at the sides of said brackets between said guides, and gangs of parallel pulverizer 110 disks carried by said arcuate gang yokes.

6. A soil pulverizer implement, comprising a draft frame provided at its sides with guide rollers and subjacent guide shoes, longitudinally extending gang yokes arranged to move between said guide rollers and shoes, and front and rear pulverizer disk gangs carried between said gang yokes and adapted to move with the latter below 115 said guide rollers.

7. A soil pulverizer implement, comprising a transversely extending draft frame provided at its ends with guide members and rollers, longitudinally extending gang yokes movable relative said guide members and on 125 said rollers, means for detachably mounting said yoke members in said guide members, and front and rear pulverizer disk gangs carried by the ends of said gang yokes and below said draft frame.

8. A soil pulverizer implement, comprising a draft frame provided with guide rollers and guide shoes, arcuate longitudinally extending gang yokes arranged between said 5 guide rollers and guide shoes, and front and rear pulverizer disk gangs carried by said gang yokes, said gang yokes being adapted to travel beneath guide rollers with the movement of said disk gangs.
- 10 9. A soil pulverizer implement, comprising a transversely extending draft frame provided with depending end brackets having spaced guide members and rollers, longitudinally extending arcuate gang yokes movable on said guide members and riding beneath said rollers, means for detachably retaining said yoke members between said 15 guide members and rollers, and front and rear pulverizer disk gangs carried by the 20 ends of said gang yokes in transverse planes at the front and rear of said draft frame.
- 10 10. In a soil pulverizer implement, a draft frame provided with guides and guide rollers, gang yokes between said guides and 25 guide rollers, gang yoke retainers for said guide yokes, front and rear parallel extending axle shafts in said gang yokes, and gangs of pulverizer packer disks on said axle shafts, the packer disks of the front gang 30 being larger in diameter than those of the rear gang.
- 11 11. In a soil pulverizer implement, a draft frame provided with guide rollers at its sides, arcuate gang yokes moving beneath 35 and adapted to pass under said guide rollers and said yoke being arranged at the sides of said draft frame, gang yoke retainers detachably mounted at the sides of said gang yokes, front and rear axle shafts carried 40 in said gang yokes, and gangs of pulverizer disks mounted on said axle shafts, the disks of the front gang being larger in diameter than those of the rear gang.
- 12 12. In combination in a land roller, a main 45 frame, floating frames, reciprocating with respect thereto at either end thereof, about points removed from said main frame, a pair of axles mounted in said floating frames, and a plurality of land rolling elements mounted 50 on said axles.
- 13 13. In combination in a land roller, of a main frame, having downwardly projecting end members on either end thereof, a floating member adjacent either end of the main 55 frame and reciprocating in the downwardly projecting members, guiding and retaining means for maintaining the floating connection between the floating member and the main frame at either end thereof, a pair of 60 axles located in either end of the floating
- frames parallel to one another, a plurality of rolling elements mounted on said axles, said axles, rolling elements and floating frames adapted to reciprocate about a point located between said axles and removed 65 from the main frame, said point being the center about which the arcuate floating frames are laid out.
14. In combination in a land roller, of a main frame, having downwardly projecting 70 end members on either end thereof, a floating member adjacent either end of the main frame and reciprocating in the downwardly projecting members, guiding and retaining means for maintaining the floating connection 75 between the floating member and the main frame at either end thereof, a pair of axles located in either end of the floating frames parallel to one another, a plurality of rolling elements mounted on said axles, 80 said axles, rolling elements and floating frames adapted to reciprocate about a point located between said axles and removed from the main frame, said point being the center about which the floating members are laid 85 out, and means of providing a rolling engagement between the floating frame and the main frame and means of providing a sliding engagement between said floating frame and end frame.
15. In combination in a land roller, of a main frame, having downwardly projecting 90 end members on either end thereof, a floating member adjacent either end of the main frame and reciprocating in the downwardly projecting members, guiding and retaining means for maintaining the floating connection 95 between the floating member and the main frame at either end thereof, a pair of axles located in either end of the floating frames parallel to one another, a plurality of rolling elements mounted on said axles, 100 said axles, rolling elements and floating frames adapted to reciprocate about a point located between said axles and removed from the main frame, said point being the center about which the floating members are laid 105 out, means of providing a rolling engagement between the floating frame and the main frame, means of providing a sliding engagement between said floating frame and end frame, a detachable means for retaining the floating frame, sliding and rolling members and the main frame in floating engagement with one another, whereby said parts 110 may be removed at will and new parts substituted for old.

In testimony whereof I have affixed my signature.

RICHARD H. GRIFFITH.
